Patented Feb. 6, 1973

226,264

FORK LIFT VEHICLE

Donald A. Gilbrech, 1302 Beechwood Ave.,
Fayetteville, Ark. 72701

Filed June 24, 1971, Ser. No. 156,604

Term of patent 14 years

Int. Cl. D12—05

U.S. Cl. D14—3

FIG. 1 is a side elevational view of the fork lift vehicle showing my new design, the opposite side being a mirror image of the side shown.

FIG. 2 is a rear elevational view thereof.

FIG. 3 is a front elevational view thereof.

FIG. 4 is a top view thereof.

I claim:

The ornamental design for a fork lift vehicle, substantially as shown and described.
